CHESTER E. RADFORD, OF ORLANDO, FLORIDA, ASSIGNOR OF ONE-HALF TO ARTHUR W. HAYES, OF ORLANDO, FLORIDA, AND ONE-HALF TO F. PAUL STEVENS, OF LAKE PLACID, NEW YORK

FIREPLACE HEATING FURNACE

Application filed January 12, 1929. Serial No. 332,008.

My invention relates to fireplaces, and it consists in the constructions, arrangements and combinations herein described and claimed.

It is an object of my invention to provide a fireplace wherein air is heated and discharged into a room, in addition to utilizing radiation of heat from the fireplace itself.

It is a further object of the invention to provide a fireplace wherein a fire-box defines passageways for admission of cold air and the exit of heated, purified air into a room.

It is a still further object of the invention to provide a fire-box of such structure as to be readily installed in the usual open fireplace.

Additional objects, advantages and features of invention will be apparent from the following description and drawings, wherein:

20 Figure 1 is a front elevation of a fireplace constructed in accordance with my invention, a portion thereof being broken away.

Figure 2 is a vertical sectional view on the line 2—2 of Fig. 1.

25 Figure 3 is a cross-section on the line 3—3 of Fig. 1.

Figure 4 is a vertical sectional view on the line 4—4 of Figure 1.

Figure 5 is a perspective view of the metallic lining.

In carrying out my invention, I make use of a fireplace, generally indicated by the reference character A, which may be of any well known construction having a fire chamber B and flue C. Within the chamber B there is disposed a fire-box composed of a back plate 1 and side plates 2. The back plate 1 has grooves 16 adjacent the ends to receive one end of the side plates 2 therewithin. The 35 joint between the grooves 16 and the plates 2 may be suitably cemented in order to provide a tight seal therebetween to prevent leakage of gases or smoke therethrough.

The plate 1 has a plurality of vertical ribs 45 17 and a horizontal rib 11 connects the ribs 17 at the upper edge, to provide a support for fire-brick as well as reinforcement of the plate.

The plates 1 and 2 in their assembled relation are of a size to lie flush with the opening

of the chamber B and stop short of the rear wall of the chamber a suitable distance, thus forming a heat compartment 8. The edges of the plates 2 engaged within the grooves 16 of the plate 1 are tapered from the bottom edge to the upper edge, thereby providing a firebox of ample heat radiating surfaces at the lower portion, with a relatively restricted throat portion for registry with the smoke flue C, in order to accommodate escape of smoke and gases. 55

Reference is now made to Fig. 5, wherein it is seen that the side plates 2 are provided with integral fins 9 and 10 disposed at the lower and upper portions of the plates, respectively. As shown in Figs. 1 and 4, these fins support fire-brick 13^a and 13^b and thus define a hot air compartment 8^a on each side of the fire-box. It should be noted that the fire-brick 13^a supported by the fin 9 is of greater width and length than the fire-brick 13^b supported by the fin 10 and stops short closely adjacent the rear wall of the chamber B. 60

The top of the rear chamber 8 is closed by fire-brick 12, one end thereof resting upon the rib 11 of the back plate while the opposite end may be supported by an angle iron 3. Intermediate T-iron support 4 may also be employed, as shown, in the event that the fire-brick 12 is of insufficient length to span the open end of the chamber. 70

The walls of the chamber 8 may be suitably lined with fire-clay 14 and asbestos 15, this being well understood in the art. 75

Upon the front face of the fireplace, I provide air inlets and outlets 6 and 7, respectively. The inlets 6 are formed at opposite sides of the fire chamber and adjacent the lower part thereof; while the outlets 7 are disposed at the upper part of the fireplace but in line with the inlets 6, as shown in Figs. 1 and 2. 80

The operation of the device is easily understood. The cold air enters the register 6, as indicated by the arrow 18 of Figure 4. 85 The air then passes through the passageway 19 and thence behind fire-brick 13^a and into heating chambers 8 and 8^a, as indicated by the arrows 20 and 21, respectively. The unequal heating of portions of the walls 1 and 90 95

2 surrounding the heating chambers 8 and 8^a cause convection currents to be set up in the air stream, thereby assuring movement of said air throughout said chambers. The 5 arrow 23 in chamber 8^a indicates the movement of the air thereinto. The air upon being heated within these chambers expands and due to its decreased density relative to the incoming cooler air is forced into the 10 restricted passage behind the fire-brick 13^b and into the passage 24, as indicated by the arrows 25 and 26. The air then passes into passageway 27 which communicates with register 7 to discharge said air back into the 15 room, as indicated by arrows 28 and 29. It is obvious that the fire-brick 13^a and 13^b being heat-storing means will serve to maintain the heating chambers at a high and more uniform temperature. It is also easily seen 20 that due to the projection of the fire-brick 13^a to the rear of the fire-brick 13^b convection currents will be set up that will augment the flow of the air from the heating chambers 8 and 8^a into the passages 24, as indicated by 25 arrows 25 and 26.

I claim:—

1. The combination of a fireplace having a flue, a fire-box in communication therewith, said fire-box comprising back and side walls, 30 lateral fins carried by said side walls, heat storing means supported by said lateral fins and forming with said side walls and the walls of said fireplace, hot air chambers upon each side of said firebox, air inlets below said 35 side chambers, arranged to discharge air to the rear of and into said side chambers and hot air outlets in communication with said side chambers.

2. The combination of a fireplace having a flue, a fire-box in communication therewith, said fire-box comprising back and side walls, 40 a lateral fin projecting from said back wall, a support projecting from the rear wall of said fireplace, heat storing means supported 45 by said fin and said support to form with said back wall and the walls of said fireplace, a hot air chamber at the rear of the fire-box, air inlets below said chamber arranged to discharge air into said chamber and hot air 50 outlets in communication with said chamber.

3. In combination with a fireplace having a back wall, a fire-box therein, said fire-box having back and side walls and being spaced from the back wall of said fireplace, the back 55 wall of said fire-box being inclined forwardly at the upper portion to form in cooperation with the walls of said fireplace a hot air chamber of varying cross sectional area, heat-storing means disposed between the upper portions of said fire-box and the back wall 60 of said fireplace and cold air inlets and hot air outlets in communication with said hot air chamber.

4. A fire-box for fireplaces or the like, comprising side walls and a back wall, fins po-

sitioned on said side walls and a fin positioned on said back wall and heat storing means supported by said fins for cooperation with the walls of said fire-box and the fireplace to define chambers for the passage of air there-through.

5. The combination of a fireplace having a flue, a fire-box in communication therewith, said fire-box comprising back and side walls, upper and lower lateral fins carried by said side walls, said upper fins being shorter than said lower fins, a fin carried by said back wall, heat storing means mounted on said side fins and said back fin and forming with the said side walls and back wall and the walls of the fireplace, inter-communicating hot air chambers upon the side and in the rear of said fire-box, air inlets below said chambers arranged to discharge air to the rear of and into said side chambers and rear chambers about the ends of said lower fins and hot air outlets comprising passages at the rear of said upper fins in communication with said hot air chambers.

In testimony whereof I hereunto affix my signature, this 9th day of January, A. D. 1929.

CHESTER E. RADFORD.
